UNITED STATES PATENT OFFICE.

LEO PLATT, OF NEW YORK, N. Y., ASSIGNOR TO CENTURY RIBBON MILLS, INC. (ERNEST & HERMAN LEVY), OF NEW YORK, N. Y., A CORPORATION OF NEW YORK.

DESIGN FOR A BUCKLE.

Application filed October 7, 1924. Serial No. 10,990. Term of patent 14 years.

To all whom it may concern:

Be it known that I, LEO PLATT, a citizen of the United States of America, residing at New York city, in the county of New York and State of New York, have invented a new, original, and ornamental Design for a Buckle, of which the following is a specification, reference being had to the accompanying drawing, forming part thereof.

I claim:—

The ornamental design for a buckle, as shown.

In testimony whereof I affix my signature.

LEO PLATT.
